UNITED STATES PATENT OFFICE.

ABRAHAM POSNER, OF BROOKLYN, NEW YORK.

DESIGN FOR A SHOE.

Application filed June 28, 1924. Serial No. 8,998. Term of patent 3½ years.

To all whom it may concern:

Be it known that I, ABRAHAM POSNER, a citizen of the United States, residing at New York, in the county of Kings and State of New York, have invented a new, original, and ornamental Design for Shoes, of which the following is a specification, reference being had to the accompanying drawing, forming part thereof.

The figure is a side elevation of a shoe showing my new design.

I claim:

The ornamental design for a shoe, as shown.

ABRAHAM POSNER.
